UNITED STATES PATENT OFFICE

HERBERT E. WHITE, OF CLEVELAND, OHIO, ASSIGNOR TO TRUSCON STEEL COMPANY,
OF CLEVELAND, OHIO, A CORPORATION OF MICHIGAN

METHOD OF LAYING OUT SHEET-METAL STRUCTURES

Application filed September 13, 1929. Serial No. 392,399.

In connection with the formation of articles of sheet metal and particularly those of relatively heavy material and in which openings must be accurately located, considerable difficulty is experienced and time and material used in determining the position of these openings in the blanks. So far as I am aware, this determination has only been accomplished by a "cut and try" method involving the formation of several blanks and shifting the holes one way or another so as to have them properly positioned in the finished product.

The object of the present invention is to provide a method by which the openings can be determined on a master blank with the utmost precision.

In the accompanying drawings:

Figure 1 is a plan view of a portion of the blank of the side rail of an automobile with the hole determining chart appearing thereon.

Figure 2 is a perspective view of the same portion after it has been stamped or formed.

Figure 3 is a view of a second blank corresponding to Figure 1 and with the position of the holes properly determined and marked.

Figure 4 is a view of the blank of Figure 3 after it has been formed.

Figure 5 is a perspective view of one of the complete side rails.

In the formation of sheet metal structures and particularly where they are of irregular shape, it is obvious that when the previously cut blank is shaped by the dies the metal is materially distorted and consequently there has been difficulty and loss of time and material in determining where the openings should be made in the blank prior to its formation, so that they will be properly positioned on the completed product.

According to the present method, a number of correspondingly shaped blanks are produced. Two of these are provided on their faces with corresponding charts. Thus in Figures 1 and 3 two blanks 6 and 6^a are employed. Each of these has placed on its face, a chart constituted of crossed lines designated respectively 7 and 7^a. The charts of the two blanks correspond accurately.

The lines may be formed in any manner and

preferably are as close as $\frac{1}{4}$ in. apart. These lines bear certain relations to pre-determined parts of the blanks. Thus in the present embodiment the blanks have openings 8 and 8^a, through which the holding pins of the dies extend for anchoring the blanks during the stamping or forming operation.

One of the blanks as 6 is then placed in the dies and stamped or bent to its final shape as shown in Figure 2. In this transformation, obviously, the bending of the material and the shaping of the part results in a distortion of the face of the sheet. The chart will obviously be correspondingly distorted. The locations of the openings desired in the completed article are then laid out on the member 6 of Figure 2 and marked thereon, for instance, by center punching as indicated at 9.

Having determined the positions of the openings, it is now only necessary to locate their position on the chart 7 and correspondingly mark them by means of the chart 7^a on the blank 6^a of Figure 3. The openings can thus be accurately determined in the blank 6^a and in fact in all other blanks of the same form, so that the openings may now be punched in the blanks, and when the blanks are formed into the final product as indicated in Figure 4, the openings as 9^a will always come in the same location as in the master form of Figure 2.

In Figure 5 a complete side rail is illustrated merely to show a complete article, it being understood that Figures 1 and 4 inclusive disclose an enlarged part of the end portion of said rail. It will be also understood that while the specific disclosure is a side rail for automobiles, the invention is not limited to this structural element but is useful in the formation of many sheet metal devices and particularly those of relatively heavy gage and involved form.

From the foregoing, it is thought that the construction, operation and many advantages of the herein described invention will be apparent to those skilled in the art without further description, and it will be understood that various changes in the size, shape, proportion and minor details of construction

may be resorted to without departing from the spirit or sacrificing any of the advantages of the invention.

What I claim, is:

- 5 1. The method of determining the location of openings in stamped articles which consists in locating corresponding charts on two blanks of the articles at the places where the holes are to be made, stamping one of said blanks to shape, determining on the chart of the stamped blank, the location of the openings, and locating said openings correspondingly on the chart of the unstamped blank.
- 10 2. The method of determining the location of openings in stamped articles which consists in forming corresponding charts of intersecting lines on two blanks of the articles at the places where the holes are to be made, stamping one of said blanks to shape, determining on the chart of the stamped blank, the location of the openings, and locating said openings correspondingly on the chart of the unstamped blank.
- 15 3. The method of determining the location of work to be done on the blanks of stamped articles prior to their stamping and consequent distortion, which consists in locating corresponding charts on two blanks of the article to be stamped, stamping one of the blanks to shape, determining on the stamped blank and with reference to the chart thereof, the proper location of the work that is to be done on the blanks prior to their stamping, and locating on the unstamped blank
- 20 by means of the corresponding chart the position of the work to be done to cause it to be properly positioned on other stamped blanks as shown by the chart of the stamped blank.
- 25 4. In testimony whereof, I affix my signature.

HERBERT E. WHITE.
